UNITED STATES PATENT OFFICE.

WILLIAM W. BELL, OF ALAMEDA, CALIFORNIA.

DIRECTION-INDICATOR FOR VEHICLES.

1,138,834.

Specification of Letters Patent.

Patented May 11, 1915.

Application filed March 16, 1914. Serial No. 824,906.

To all whom it may concern:

Be it known that I, WILLIAM W. BELL, a citizen of the United States, residing at Alameda, in the county of Alameda and State of California, have invented new and useful Improvements in Direction-Indicators for Vehicles, of which the following is a specification.

This invention relates to improvements in direction indicators for vehicles and the like.

The object of the invention is to provide simple, practicable and compact electrically operated mechanism of the character described which is particularly adapted to be attached to the rear of an automobile.

Another object of the invention is to provide a mechanism which is automatic in operation, and by which the direction of the car will be indicated to another car following in the rear.

Another object is to provide means for automatically breaking the circuit to render the mechanism inoperative when the engine of the car is stopped.

Another object of the invention is generally to improve this class of apparatus so as to reduce the number of accidents and generally decrease the difficulties of the traffic problem in crowded districts.

Further objects will hereinafter appear.

The invention consists of the parts and the construction and combination of parts as hereinafter more fully described and claimed, having reference to the accompanying drawing in which—

Figure 1 is a diagrammatic view of the electrical circuits and connections by which the electromagnets of the direction indicating mechanism are operated. Fig. 2 is a detail view of one of the electromagnets. Fig. 3 is a front view partly broken away showing the direction indicating device. Fig. 4 is a plan section on line X—X, Fig. 3.

Referring to the drawings, A indicates a rectangularly shaped casing which is divided into upper and lower compartments 2 and 3, in the upper compartment of which is formed a glass covered display opening 3^a. Suitably secured in the lower compartment of the casing is a plurality of angularly disposed solenoid magnets 4, 5 and 6, and pivotally mounted as at 7, 8 and 9 in juxtaposition with relation to same are a plurality of display plates 10, 11 and 12.

Suitably secured in the lower compartment of the casing is a plurality of angularly disposed solenoid magnets 4, 5 and 6, and pivotally mounted as at 7, 8 and 9 in juxtaposition with relation to same are a plurality of display plates 10, 11 and 12.

The several signs shown are adapted to

be elevated into the dotted line position shown at 13, or into register with display opening 3^a, and are provided for the purpose of displaying such words as Stop, Right and Left, or the like, which when raised into register with display opening 3^a will immediately indicate to a car approaching from the rear the intended direction or movement of the car displaying the sign.

Each magnet is provided with a movable core, as indicated at 14, 15 and 16, and each core is in turn connected through links 17, 18 and 19 with lever extensions 20, 21 and 22 formed on the respective plates 4, 5 and 6 as shown. The weight of each display plate is just a little in excess of the combined weight of the core and link to which it is attached, and the plates will thus act as a counterweight to normally retract the cores from their respective magnets as indicated in Fig. 3. Means have however been provided for the purpose of balancing the weight between the plates and the connected movable cores. This is accomplished by forming a pocket 23 in each core into which shot or like material indicated at 24 may be placed for the purpose of securing the desired balance. The upper end of the pocket is covered by a movable plate 25, and this prevents the counter-weighing material 24 from being displaced or lost. A perfect adjustment between the movable cores and the display plates may thus be secured, and also makes it possible to vary the size and weight of the several parts. The downward movement of the several cores, together with the elevated position of their connected signs is in each instance regulated and adjusted by a set-screw 26 with which the respective cores engage when attracted by the coils.

The several magnets here shown are automatically operated for the purpose of displaying the respective signs, and this is accomplished in the following manner: Referring to Fig. 1, B indicates the steering post of a car, and 27 a lever arm which is secured to and movable with same. Suitably secured within the arc of travel of arm 27 is a pair of flexible contact members 28 and 29, and similarly positioned with relation to the brake lever C of the car is another flexible contact member 30. Magnet 4 is connected on one side through wire 31 with contact 29, and magnet 6 is connected on one side through wire 32 with contact 28. The opposite terminals of the respective

magnets are in turn connected through a wire 33. Magnet 5 is connected on one side through wire 34 with the positive side of a suitable form of battery, indicated at 35, and the opposite terminal of magnet 5 is connected through wire 36 with contact member 30. The steering post B, together with the brake lever C is connected through wires 37 and 38 respectively with one side of an automatic circuit-breaker 53, hereinafter to be described, and the other side of the circuit-breaker is connected through wire 40 with the negative side of the battery.

41 indicates in general a secondary circuit-breaker which consists of a magnet 42 and an armature 43. The armature here shown is slidably mounted on a pair of rods 44, and coil springs 45 surrounding the rods are interposed between the magnet and the armature for the purpose of normally holding this in engagement with a pair of contact members 46 and 47. Magnet 42 is connected on a shunt circuit through wires 48 and 49 with magnet 5, and contact member 46 is connected through wire 50 with wire 33, while contact member 47 is connected through wire 51 with wire 34.

The function and operation of the secondary circuit-breaker just referred to will later be described. The main circuit-breaker indicated at 53 consists of a shaft 52 which may be direct connected with the engine of the car, indicated diagrammatically at D. Surrounding said shaft, and insulated from same is a cylindrically shaped casing 53, and pivotally secured to shaft 52 as at 54 is a weighted lever 55, which is adapted to be thrown outwardly into contact with the inner surface of the cylindrical casing when shaft 52 is revolving to form a circuit between wires 39 and 40, and which is also adapted to be retracted to open the circuit between said wires when the engine is stopped. This is accomplished by a spring 56 which is adapted to normally retract the lever when the shaft is stationary. The circuit between the battery and the several parts of the mechanism will thus be automatically opened the moment the engine 50 of the car is stopped, thus rendering the mechanism inoperative and preventing any waste of current from battery 35.

The operation of the device will be as follows: If the car is traveling straight ahead no circuit will be closed, and no sign will be displayed. The moment the driver turns the wheel to the left, a circuit will immediately be closed through post B, lever 27, contact 29, wire 31, magnet 4, wire 50, contact 46, armature 43, contact 47, wires 51 and 34 to the battery. From the battery the current will pass out through the negative side, wire 40, casing 53, weighted lever 55, shaft 52 and wires 39 and 37 back to the post. The circuit is thus closed through

magnet 4 which energizes same, causing core 14 to be retracted, thus transmitting motion through link 17 and lever 20 to raise plate 10 into display position, or in register with opening 3^a. The sign, or plate displaying the word Left will remain in this position as long as the car is turning to the left, or as long as arm 27 is in engagement with contact 29. The circuit will, however, be open the moment arm 27 and contact 29 are separated, which takes place the moment the car straightens out. The circuit is thus automatically opened, causing magnet 4 to be de-energized. Core 14 is thus released and allowed to return to normal position through the medium of plate 10, which is sufficiently heavy to drop down into the lower compartment of the case. The circuit through magnet 6 which actuates the plate having Right printed thereon is closed the moment arm 27 is brought into engagement with contact 28 which takes place when the wheel is turned to the right. This circuit can be traced as follows: Commencing with the negative side of the battery the current passes through wire 40, casing 53, weighted lever 55, shaft 52, wire 39, wire 37, post B, arm 27, contact 28, wire 32, magnet 6, wire 33, wire 50, contact 46, armature 43, contact 47, wire 51 and wire 34, which in turn returns to the battery. The circuit through magnet 6 thus established will elevate the plate having Right printed thereon into register with display opening 3^a, and the plate will be allowed to drop into the lower part of the casing the moment magnet 6 becomes deenergized. The circuit magnet 5 for the purpose of displaying the stop sign is closed the moment brake pedal C is depressed in the direction of arrow a. This circuit can be traced as follows: Commencing with the negative side of the battery the current passes through wire 40, casing 53, weighted lever 55, shaft 52, wire 39, wire 37, lever C, contact 30, wire 36, magnet 5 and through wire 34 back to the positive side of the battery. Magnet 5 is deenergized, however, the moment the brake pedal is released, and the Stop sign is similarly allowed to drop into the lower compartment of the casing raising its connected core into the position shown.

The circuit-breaking mechanism indicated at 41 is provided for the purpose of releasing either the left or right display sign when it is desired to stop the car while either one of these signs are being displayed, for instance, supposing the car is turned to the left around the corner and an obstruction is met which makes it necessary to stop the car it is then necessary to lower the display plate having Left marked thereon and elevate the plate having Stop shown thereon. This could not be accomplished if the Left display plate was not released. The automatic release of same is accomplished in the fol-

lowing manner: Supposing arm 27 is in engagement with contact 29 and that the circuit is closed through magnet 4 which holds the display plate having Left marked thereon in the elevated position. An obstruction 5 is met which necessitates the stopping of the car. The brake-pedal C is consequently depressed in the direction of arrow α , and the circuit controlled by lever C and contact 30 will thus immediately be closed. Magnet 5 being on this circuit is energized by the passage of current through same, and magnet 42 being shunted on said circuit through wires 48 and 49 will also be energized. The 10 core of magnet 42 will consequently attract armature 43, thus opening the circuit between contacts 46 and 47. The circuit through magnet 4 can only be closed when armature 43 is in engagement with contacts 15 46 and 47. It can thus be seen that the moment armature 43 is attracted by the core of magnet 42 the circuit through magnet 4 will immediately be opened and this will 20 consequently become deenergized, and permit the sign having Left displayed thereon to be released and dropped into the lower 25 compartment of the casing. The action is similar when magnet 6 controlling the display sign having Right marked thereon is energized. If the car is turning to the right and the connected sign is displayed, and it is necessary or desirable to stop the car, it is immediately accomplished by the closing 30 of the circuit through magnet 5 through the medium of brake lever C and contact 30. The circuit through magnet 6 is broken 35 through circuit-breaker 41 by the opening of the circuit through contacts 46 and 47. It is thus impossible to display more than 40 one sign at one time, and it is furthermore impossible to apply the brake lever and stop the car whether traveling on the right-hand curve or the left-hand curve without displaying the stop sign. The vehicle following 45 in the rear is thus given a warning, and collisions of any kind will be prevented.

The mechanism constructed as here shown is absolutely automatic in operation; as the direction of the car actuates the sign-displaying mechanism, no thought or care on the part of the driver is necessary, and the most positive result is secured.

The centrifugally actuated circuit-breaking mechanism, indicated at 53 being 55 directly connected to the engine, or operated or driven by same, will keep the circuits closed as long as the engine is running, but will immediately open the circuit to the battery the moment the engine is stopped, as 60 spring 56 will immediately attract the lever and break the circuit between shaft 52 and casing 53. This will render the mechanism inoperative and prevent any unnecessary waste of current. It can easily be understood 65 that if a circuit-breaker or similar

means is not provided it would be possible that the driver might leave the car with the front wheels slightly turned or the brake set. This would in either instance, close the circuit through the battery and leave some 70 sign in the display position which is absolutely unnecessary, and might cause the battery to run down in a short time.

The pivotal mounting of the display signs, together with the weight of same eliminates 75 the use of extra counterweights or retracting springs, thus simplifying the construction and reducing the cost of manufacture.

The materials and finish of the several parts of the mechanism may otherwise be 80 such as the experience and judgment of the manufacturer may dictate, and I wish it understood that various changes in form, proportions and minor details of construction may be resorted to within the scope of 85 the appended claims, and that I do not wish to limit myself to the specific design and construction here shown.

Having thus described my invention, what I claim and desire to secure by Letters 90 Patent is:

1. The combination with a car, of a casing secured to the rear end of same, a plurality of signs pivotally mounted in said casing, a solenoid magnet connected to each 95 sign, a source of current supply means automatically controlled by the steering and braking mechanism of the car for closing a circuit through one or another of said magnets to raise the connected sign into display 100 position, said means operating to prevent the display of more than one sign at the time, and comprising a core magnet connected in shunt circuit with one of the solenoid magnets, an armature actuated by the 105 core magnet, and a pair of contact members with which the armature is adapted to engage to open or close the current through the other solenoid magnets.

2. The combination with a car, of a casing secured to the rear end of same, a plurality of signs pivotally mounted in said casing, a solenoid magnet connected to each sign, a source of current supply means automatically controlled by the steering and 110 braking mechanism of the car for closing a circuit through one or another of said magnets to raise the connected sign into display position, said means operating to prevent the display of more than one sign at 115 the time, and means for opening the circuit between the magnets and the source of current supply when the engine of the car is stopped, said means comprising a centrifugally actuated circuit-breaker driven by the 120 engine.

3. In combination with a car, electrically operated direction signals actuated by the steering mechanism, an electrically operated stop indicating signal actuated by the car 125

4
brake, and a single electrically energizable means common to and independent of and for controlling each of the direction signals whereby upon each operation of the stop signal said single means will be actuated to open the circuit through either of said direction signals.

5. In combination with a car, direction signals, solenoid magnets for actuating said signals by movement of the steering mechanism, a stop signal, a solenoid magnet for actuating the stop signal by movement of the car brake mechanism, and electrically energizable means common to and independent of the direction signal magnets and operated upon energization of the stop signal magnet to open the circuit through both of said direction signal magnets, said circuit breaker being independent of the circuit closing means.

10. In combination with a car and a series of signs, a solenoid magnet for operating each sign, and means controlled by the steering and braking mechanism for closing a circuit through said magnets to move the sign thereof to display position and to prevent the display of more than one sign at a time including a core magnet connected in 15. shunt circuit with one of the solenoid magnets, an armature actuated by the core magnet, and a pair of contacts with which the armature is adapted to engage to open or 20. close the circuit through the solenoid magnets.

25. In combination with a car, direction signals, solenoid magnets for actuating said signals by movement of the steering mechanism, a stop signal, a solenoid magnet for actuating the stop signal by movement of the car brake mechanism, and electrically energizable means common to and independent of the direction signal magnets and operated upon energization of the stop signal magnet to open the circuit through both of said direction signal magnets, said circuit breaker being independent of the circuit closing means.

30. In testimony whereof I have hereunto set 35 my hand in the presence of two subscribing witnesses.

WILLIAM W. BELL.
